UNITED STATES PATENT OFFICE.

JERRY D. WILDE, OF CLEVELAND, OHIO.

SANITARY GARBAGE DRAIN.

Application filed March 29, 1926. Serial No. 98,281.

My invention relates to a device for draining the liquid from garbage.

It is an object of my invention to provide an improved type of draining device 5 of this character of practical construction, and one which can be economically manufactured.

It is a further object of my invention to provide a garbage drain adapted to be connected to the sewerage system of a residence 10 or other building in which the drain is employed, whereby any liquid drained from the garbage will enter the sewerage system.

My invention specifically contemplates 15 the provision of a garbage drain adapted to be connected to the drain pipe of the usual kitchen sink, but it will be understood that the invention is applicable to other uses and may be connected to other branches of the 20 sewer system.

I further contemplate the utilization of the suction action created by the flow of liquid through the sink drain pipe or other sewer connection, to aid in the draining of 25 excess liquid from the garbage, and further to prevent the accumulation of gases in or the emitting from the garbage drain of offensive odors.

It is an additional object of my invention 30 to so support my improved garbage drain that it can be moved from an accessible position into the normally waste space beneath a kitchen sink and swung from such position back into accessible position without rendering the drain inoperative.

In the drawings forming a part of this 35 application, like reference characters refer to like features.

Fig. 1 is a side elevational view, showing 40 my invention applied to the drain pipe of a sink;

Fig. 2 is a detail view, showing the construction of the garbage retainer in its relation to the drain;

Fig. 3 is a detail view of the pivotal connection for permitting movement of the receptacle relative to the drain pipe; and

Fig. 4 is a detail view of the means for connecting the device to a drain pipe.

For simplicity of description, I have illustrated my invention as applied to the drain pipe of the ordinary kitchen sink. It

will, however, be understood that it is equally applicable to other sewer connections.

As shown, the sink 1 is provided with the usual drain pipe 2, having a conventional trap.

My invention comprises the outer casing 3, which is connected to the drain pipe 2 through the medium of the pipe connections 4 and 6, which are joined together by a pivotal connection 5, which permits swinging of the section 4 with respect to the section 6, without cutting off communication between the outer casing 3 and the drain pipe 2. The section 6 is secured to the drain pipe 65 2 through the medium of the clamp member 7, the arrangement being such that the entire device can be assembled and secured to a conventional drain pipe without any change in the sewerage system. 70

The construction of the garbage receptacle is more clearly shown in Fig. 2, wherein the reference character 8 indicates a casting secured to the bottom of the outer casing 3, into which casting 8 the pipe section 75 4 is adapted to be threadedly secured, the outer casing 3 being supported by the pipe section 4.

A garbage container 9, having perforations 10 for the passage of liquid therefrom, 80 is adapted to be inserted into the outer casing 3. The bottom of the container 9 is held slightly spaced from the bottom and side walls of the outer casing 3, to permit any liquid passing through the perforations 85 10 to flow out of the casing 3 through the pipe connection 4, and thence through the pivotal connection 5 through the pipe section 6 to the sink drain 2. The garbage container 9 is provided with handle members 90 for permitting its ready insertion and removal from the outer casing 3.

For the purpose of preventing minute particles, such as coffee grounds and the like, from passing through the perforations 95 10 and clogging up the pipe connections between the outer casing 3 and the drain pipe 2, I provide a small insert 12, which is adapted to be supported by the side walls 100 of the garbage container 9. This receptacle 12 may be provided with a fine screen 12', to permit liquid to drain from minute particles without allowing such particles to pass into the outer casing 3 through the perfora-

- tions 10. A cover 11 is provided for tightly closing the outer casing 3 when the garbage containers 9 and 12 are positioned therein.
- 5 The pivotal connection 5 between the pipe sections 4 and 6 is constructed of an outer casing 13, secured to the pipe section 6, as shown at 14 (see Fig. 3). The outer casing 13 is provided with the radially extending 10 slot 15. Within the casing 13 is pivotally mounted an inner casing 16, to which is secured the pipe section 4, as shown at 17. The arrangement is such that the pipe section 4 can be swung with respect to the pipe section 6, the slot 15 permitting the section 4 and the inner casing 16 to swing relatively to the outer casing 13 and pipe section 6.

It will be seen that, by the provision of the pivotal connection between the pipe sections 4 and 6, the casing 3 can be swung from the position shown in full lines in Fig. 1 to the position shown in dotted lines, without in any way affecting the open communication between the casing 3 and the 20 drain pipe 2. This is particularly advantageous because it permits the moving of the receptacle into a position to receive garbage and thereafter permits the swinging of the receptacle into the normally waste space beneath the sink, in which position the drain continues to efficiently function.

The whole device so far described is secured to the drain pipe 2 through the clamping device 7, which comprises the two cooperating members 18 and 19, adapted to be securely clamped to the pipe drain 2 through the medium of the bolts 20. The pipe section 6 is connected to the member 18, as shown at 21.

40 It is to be particularly noted that the connection between the garbage drain and the sink drain pipe 2 is made at a point below the trap. This prevents any odors from arising through the sink. Furthermore, the 45 frequent flushing of water from the sink through the drain pipe 2 creates a suction action upon the garbage in the garbage receptacle through the pipe sections 4 and 6, which augments the draining action of the 50 garbage in the container 9. In addition to this function, the liquid flushed through the line 2 from the sink 1 also draws all of the gases and resultant odors accumulating in the garbage receptacle therefrom to the 55 sewer pipe 2, thus avoiding the escape of unpleasant odors from the garbage drain.

From the foregoing, it will be seen that I have provided an efficient and sanitary garbage drain, which is applicable to the conventional form of sink drain pipes without any material change thereof.

What I claim as my invention is:

1. The combination with a sewer drain pipe from a sink of a garbage drain, consisting of an outer casing and a perforated

garbage receptacle inserted in said outer casing, a conduit connecting said outer casing with said drain pipe at a point below the normal sewer trap, and means intermediate the length of said conduit for permitting relative movement of said outer casing with respect to said drain pipe, while open communication is maintained between said casing and drain pipe through said conduit. 70

2. In a device of the class described, the combination with a drain pipe from a sink of a garbage drain, comprising a garbage-receiving receptacle and a conduit connecting said garbage-receiving receptacle with said drain pipe, and means for permitting said garbage-receiving receptacle to be swung to a position beneath the sink, while said conduit is open. 75

3. In a device of the class described, the combination with a drain pipe from a sink of a garbage receptacle, said garbage receptacle comprising an outer casing and an insertable perforated container, pipe sections connecting said outer casing with said drain pipe, means intermediate said pipe sections for permitting movement of said outer casing into a position beneath the sink, without closing said pipe sections. 80

4. In a device of the class described, the combination with a drain pipe from a sink of a garbage drain, comprising a garbage-receiving receptacle, a fixed conduit connected to and projecting from said drain pipe, a second conduit connected to said garbage-receiving receptacle and pivotally mounted on the free end of said fixed conduit, whereby said garbage-receiving receptacle may be swung relative to said drain pipe and fixed conduit. 95

5. In a device of the class described, the combination with a drain pipe from a sink of a garbage receptacle, a fixed conduit connected to said drain pipe and projecting toward the front face of the sink, a second conduit connected to said garbage receptacle, a pivotal connection between the free end of said fixed conduit and the free end of said second conduit, said pivotal connection permitting movement of said garbage receptacle from a position in advance of the front wall of the sink to a position to the rear of the front wall of the sink. 100

6. In a device of the class described, the combination with a drain pipe from a sink of a garbage drain, said garbage drain comprising a garbage-receiving receptacle and a conduit connecting said garbage-receiving receptacle with said pipe, and means associated with said garbage-receiving receptacle for permitting the same to be swung from a position in advance of the front wall of the sink to a position to the rear of the front wall of the sink. 110

In testimony whereof I affix my signature.
JERRY D. WILDE.
